UNITED STATES PATENT OFFICE.

MICHAEL HUGHES, OF SAN FRANCISCO, CALIFORNIA.

PLASTIC COMPOSITION FOR TAILORS' CUTTING-BOARDS, AND FOR OTHER PURPOSES.

SPECIFICATION forming part of Letters Patent No. 286,442, dated October 9, 1882.

Application filed October 18, 1882. (No specimens.)

To all whom it may concern:

Be it known that I, MICHAEL HUGHES, a citizen of the United States, residing at San Francisco, California, have invented certain new and useful Improvements in Plastic Compounds for Tailors' Cutting-Boards and other Purposes, of which the following is a specification.

My invention has relation to plastic compounds that may be molded or compressed in any shape or style, as may be desired, and is applicable to a variety of purposes in ornamentation, in place of stone, wood, or any of the natural products which would require cutting or carving.

In practice I make a compound consisting of sawdust, rice or rye-flour, india-rubber or gutta-percha, linseed-oil, and soap-boilers' waste, and in some cases a proportion of tar, pitch, or similar bituminous substance, which may be melted and thoroughly mixed in that state, and then cast in suitable molds or compressed in any desired form; or it may be simply compressed in slabs or blocks, and cut, as desired, for use. I vary the proportions to correspond to the use to which the compound is to be applied.

One way of making my improved composition is as follows: sawdust, ten (10) parts; rubber or gutta-percha, five (5) parts; rice or rye-flour, four to five (4 to 5) parts. Linseed-oil or

soap-boilers' waste is added in such quantity as to give the mass a proper consistence. It may then be run into molds and allowed to harden; or it may be compressed into any desirable form.

I have cast or formed the above compound into boards for use by tailors for cutting out garments, and for the various uses of cutters in general. The peculiar composition of the board tends to preserve the edge of the cutting-tool, and it consequently lasts much longer, and requires less sharpening, than where ordinary form of board is used, and there being no grain in my improved board, the cutting can be performed with greater ease.

Having thus described my compound, what I claim as new is—

An improved plastic composition, consisting of sawdust, flour, rubber or gutta-percha, linseed-oil, and soap-boilers' waste, with or without the addition of a bituminous substance, as set forth.

In testimony whereof I affix my signature, in presence of two witnesses, this 12th day of October, 1882.

MICHAEL HUGHES.

Witnesses:

E. H. BRADFORD,
H. J. ENNIS.
